STRINGED MUSICAL INSTRUMENT

John W. McBride, Burbank, Calif.

Application January 26, 1943, Serial No. 473,601

21 Claims. (Cl. 84—315)

1

This invention relates to a musical instrument, and more particularly to an instrument having one or more tensioned strings, such as a guitar, banjo or violin.

The free vibrating length of any of the strings determines the pitch of the musical note produced by the string. The conventional manner of determining the free length is by "stopping" the string with the fingers. In some forms of instruments, it has been proposed to provide a key mechanism, operable adjacent the end of the neck, for mechanically adjusting the free vibrating length of the string.

For example, such an arrangement is described and claimed in an application, filed on April 14, 1941, in the name of John W. McBride, under Serial No. 388,379, now Patent No. 2,316,799, granted April 20, 1943. It is one of the objects of this invention to provide a different, simple form of mechanism for determining the free vibrating length of the string.

It is another object of this invention to provide a mechanism of this character that permits the use of the hand in a natural position, while the mechanism is operated, the fingers that are employed for this purpose extending in the direction of the strings, rather than in a direction transverse thereto.

In the prior application hereinabove identified, the lower side of the tensioned string is arranged to be contacted by a crest formed on a rotatable rod or bar. Angular adjustment of the rod or bar causes a corresponding variation of the point where the crest contacts the string to determine its free vibrating length. By the aid of the present invention, it is not necessary that the crest (whether continuous or interrupted) progress angularly about the axis of the bar. The crest may instead be placed on the side of the bar; the bar is moved past the string, the position of the crested side being thereby altered to cause any selected part of the crest to contact the string.

This motion of the bar can be arranged conveniently in a direction toward and from the body of the instrument, in its movements past the string. However, it is possible to move the bar in other directions, so long as the bar progresses past the string and the crest is caused to press against the string. It is accordingly another object of this invention to provide a simple form of mechanism of this general character capable of determining the free vibrating length of the string.

It is another object of this invention to make it possible to transmit the string vibrations to

2

an electric pick-up device in a simple and highly effective manner; and particularly by members that transmit the vibrations to the device by physical contact.

5 This invention possesses many other advantages, and has other objects which may be made more easily apparent from a consideration of several embodiments of the invention. For this purpose there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawings:

Figure 1 is a side elevation of an instrument incorporating the invention;

20 Fig. 2 is an enlarged plan view of the instrument illustrated in Figure 1;

Fig. 3 is a fragmentary enlarged longitudinal sectional view, taken along the plane 3—3 of Fig. 2;

25 Fig. 4 is a sectional view, taken along the plane 4—4 of Fig. 3;

Fig. 5 is a sectional view, taken along the plane 5—5 of Fig. 3, one of the bars determining the free vibrating length of a string being shown 30 in a depressed position;

Fig. 6 is a plan view of a modified form of bar that may be utilized in connection with the invention;

35 Fig. 7 is a side elevation of the bar illustrated in Fig. 6;

Fig. 8 is an enlarged fragmentary side view of a bar, such as illustrated in Figs. 6 and 7, shown in cooperative position with a tensioned string;

40 Fig. 9 is a plan view of a modified form of instrument incorporating the invention;

Figs. 10, 11 and 12 are sectional views, taken respectively along planes 10—10, 11—11 and 12—12 of Fig. 9;

45 Figs. 13, 14, 15 and 16 are fragmentary sectional views showing modified forms of the bars for determining the free vibrating length of a string;

Fig. 17 is a pictorial view of one of the bars used in connection with the instrument of Fig. 1;

50 and

Fig. 18 is a plan view on an enlarged scale of the mounting means for the bars of Fig. 1.

In the form of the invention illustrated in Figs. 1 to 5 inclusive, 17 and 18, there is illustrated a body 1, shown as having the configuration of a

violin. It is provided with a neck 2, terminating in a scrolled peg board 3.

Extending above the body 1 and the neck 2 are a plurality of tensioned strings. Eight of such strings are shown in the present instance, numbered from 4 to 11 inclusive. These strings are shown as appropriately supported in notches, such as 12 (Fig. 3) formed on a bridge 13. Since, in the form under discussion, a violin type instrument is disclosed in which the strings are arranged to be set into vibration by a bow moving transversely of the strings, the bridge 13 is upwardly arched for supporting the strings at different heights respectively above the body of the instrument. Thus, the strings considered together are in a convex configuration across the body. The right hand ends of these strings may be anchored in an anchor piece 14, appropriately attached to the tail portion of the instrument.

Each of the strings 4 to 11 inclusive is adapted to be tensioned, as by the aid of conventional pegs 15 extending through the scrolled portion 3. A supplemental bridge structure 16 (Figs. 1, 2 and 3) is arranged adjacent the left hand end of the neck portion 2.

A plurality of adjustable bars is provided for making it possible to adjust the free vibrating lengths of the strings 4 to 11 inclusive. For example, a bar 17 (Figs. 3, 4, 5 and 17) is provided for adjusting the free vibrating length of the string 7. In the present instance this adjustable bar 17 is also utilized for adjusting the free length of the adjacent string 6.

For this purpose the bar 17, which may be of hollow tubular configuration, is shown as provided with crests 18 and 19 disposed on opposite sides of the bar. These crests extend generally longitudinally of the bar 17. They press against the strings where the strings cross the crests; and thereby the free length of the string depends upon the point where the string crosses the crest. To compensate for the increased freedom of the strings in their central positions where the distance to either bridge 13 or 16 is relatively great, the crests bulge slightly in their mid portions toward the respective strings. This bulge is shown exaggerated in Fig. 6, in connection with a modified form of bar which will be described herein-after. Furthermore, since strings 6 and 7 adjacent bridge 13 are at different heights above the body of the instrument and, adjacent bridge 16, at substantially the same height, the bar 17 is of substantially rectangular cross section at its end adjacent bridge 16, as shown in Fig. 4; and is skewed or twisted at an increasing angle toward bridge 13 in accordance with the difference in heights of strings 6 and 7 above body 1 (see Fig. 5).

The bar 17 is movable past the strings 6 and 7 in such manner that the longitudinal axis of the bar moves in a plane. The apexes of the crests 18 and 19 also move substantially in planes that are parallel to this plane. The strings 6 and 7 extend parallel with said planes and transversely of the direction of movement of the bar. Thus, in the form illustrated, the bar 17 is movable downwardly toward the body 1 between the strings 6 and 7 (see Figs. 4 and 5). The lateral distance between strings 6 and 7 is slightly less than the lateral distance across the bar from apex to apex of the crests 18 and 19 at any point along the crests. Accordingly the strings 6 and 7 are resiliently maintained in contact with a point along the crests 18 and 19.

The maximum free length of a string, such as

in Fig. 3, is obtained when bar 17 is in one of its extreme positions.

The crest 18 is in contact with the string 7 at the point 20, near the left hand end of the bar 17. The string 7 is shown as forming an acute angle with the crest 18; nevertheless, the point of crossing of the string 7 over the crest 18 at the maximum free vibrating position is rendered accurate and definite by providing an extension 21 of the crest at the left hand end, and having a direction more nearly normal to the string. Thus, this maximum length may be maintained even for slight misalignments of bar 17, that may occur when the bar is in its extreme upper position.

The bar 17, however, may be moved downwardly in a manner to be hereinafter described, to assume another extreme position illustrated in dot and dash lines in Fig. 3. This extreme position is also indicated in the section, Fig. 5. Thus, the crest 18 in this position contacts the string 7 at a point 22 corresponding to the shortest adjusted length of the string.

Crest 18 may have an extension 23 at its right hand extremity, serving the same function as extension 21.

In the course of movement of the bar 17 from between its two extreme positions illustrated in Fig. 3, the free vibrating lengths of string 7 is correspondingly varied from the maximum illustrated in full lines, to the minimum illustrated in dot and dash lines.

The movement of the bar 17 is such that as it moves the strings 6 and 7 contact progressively different points of the crests. The crest 19, contacting the string 6, may be formed similarly to the crest 18, and operates in the same manner, to determine the free vibrating length of that string.

Conveniently, the bar 17 may be arranged to move angularly to effect adjustment of the free vibrating length. For this purpose bar 17 is shown as fastened to a spring hinge finger 23. This finger is shown as formed integrally with and extending upwardly at a slight angle from a base plate 24 (Figs. 1, 2, 3 and 18) supported on the body 1. The finger 23 is fastened in any appropriate manner to the end portion 25 of the bar 17. Downward pressure on bar 17 will cause the bar to move downwardly, flexing finger 23, the resilience of this finger being sufficient to return bar 17 to its normal position upon removal of such pressure.

Manipulation of the bar 17 is effected by the aid of the key 25 (Figs. 3 and 4) carried by the left hand end of the bar 17. This key 25 is shown as accommodated in a cavity or recess formed below neck 2 and extending beneath the scrolled portion 3. This recess extends entirely through the instrument, thus serving to accommodate the bar 17 when it is in the depressed position shown in dot and dash lines in Fig. 3.

The fingers of the player, for manipulation of such keys as 25, can extend generally in a direction corresponding to the length of the neck. These manipulations are accomplished by inserting the fingers into the recess 26, from below the instrument.

A projecting edge 27 of the board 3 is formed at the top of the recess 25, to serve as a stop for limiting the upward movement of the bar 17. The resilient finger 23 urges the bar 17 into the full line limiting position of Fig. 3 when the key 25 is released by the player.

Similarly, a projection 28, illustrated in Fig. 3

extends toward the left from the lower portion of the neck 2 to serve as a limiting stop against the lower portion of the key 25. By appropriate curving of the bar 17 as viewed in Fig. 3, the angle of intersection between the crest 18 and the string 7 can be kept substantially constant over the entire movement of the bar 17 between its extreme positions. This angle is large enough to form a definite place of stopping the string.

The foregoing description relates to the bar 17, which carries crests 18 and 19 capable of cooperating with the adjacent strings 6 and 7. Other types of bars can be used, having one or more crests. As examples of such bars, attention is invited to bars 29 and 30, (Figs. 2, 4 and 5). These bars quite similar to bar 17, but carry only the single crests 31 and 32, respectively cooperating with the strings 4 and 5. These bars are also mounted on spring fingers 33 and 34 respectively, formed on the metallic base 24. The bars 29 and 30 likewise terminate in key portions 35 and 36, extending into the recess 26.

In another form of bar shown at 37, two parallel sections, 38 and 39, are provided, each quite similar to bar 17 and joined for common movement by a plurality of U-shaped or fork-like bars 82. Each of the sections carries a pair of crests 40, 41 and 42, 43; crests 40 and 41 cooperate with the strings 8 and 9; crests 42 and 43 cooperate with the strings 10 and 11. A common key 44 operates the composite bar 37.

As shown most clearly in Fig. 2, the sections 38 and 39 are joined to a common spring finger 81, carried by base 24. Due to the provision of the fork-like connection 82, the strings 9 and 10 do not interfere with the movement of bar 37 (Fig. 5). Key 44 (Fig. 4) is shown wide to conform to the overall width of sections 38 and 39.

By appropriate manipulation of the four keys that extend into the recess 26 from below the neck, each of the bars 17, 29, 30 and 37 may be controlled as desired. The instrument may conveniently rest on the lap of the player, or held closely to the body if the player is in a standing position, much as a guitar may be held; or if it be necessary to use a bow, the instrument can be supported as a conventional violin. The hand of the player can be kept in a comfortable, normal, unstrained position while the keys are moved.

While it is possible to produce an appropriate volume of sound by the design of the hollow body portion 1, in the present instance an electrical pick-up device 45 (Fig. 3) is provided, which may be secured in body 1 in any desired manner. This pick-up device is shown as in immediate contact with the base of the spring hinge structure 24, which is attached to the pick-up by screws 24a. When mechanical vibrations are transmitted to the device 45, corresponding electrical impulses are produced in a circuit, which, as is well understood, leads to an appropriate sound amplifying system. Plucking or otherwise causing vibrations of any of the strings sets up a corresponding vibration in the bars 17, 29, 30 and 37, due to the physical contact of the bars with the strings. From the bars these vibrations are transmitted to the spring fingers 23, 33, 34 and 81 to the base 24, and thence to the pick-up device 45. This action supplements the transmission of such vibrations in the usual manner and improves the output of the pick up. The bridge 13 is of arch-like form and spans the pick-up 45, due to the gap or opening 13-2. The bridge 13 is urged against body 1 by the tension of strings 4 to 11, 70

and is held in place thereby, no fastening means being provided.

The tone control as well as intensity of response of the sound reproducing system can be 5 adjusted by the aid of a control device 46 (Figs. 3 and 4). This device 46 is shown as mounted in a recess 47 communicating with the main recess 26. Device 46 may be provided with a control arm 48 adapted to be controlled by the thumb of the 10 player. This control arm 48 extends through an appropriate slot in the neck 2, and through a slotted guide plate 49. The control arm 48 is joined to rotatable stem 50 of the device 46, whereby movement of the arm about the axis 15 of the stem 50 causes a corresponding variation in setting of the device 46. Conductors 51 (Figs. 3 and 4) are shown as leading from the pick-up device 45 to the device 46.

Figs. 6, 7 and 8 illustrate a modified form of 20 bar 52 that has a continuous crest 53 on one side, and a discontinuous crest on the other side. This discontinuous crest is formed as a series of points 54. Each of these crests is bulged outwardly as 25 previously mentioned, the extent of the bulge being exaggerated. Lines 83, 84 parallel to the plane in which bar 52 moves are shown in contact respectively with the highest points of the crests. However, as in the case of a continuous 30 crest, the apexes of the points 54 fall substantially in a flat plane that moves past the corresponding string.

When the bar 52 is used, the string 55 (Fig. 8), 35 may be controlled by the points 54 of bar 52. The angular movement of the bar 52 causes these points to pass successively from one side of the string to the other. In the particular position shown in Fig. 8, and assuming that the bar 52 is moving downwardly, the apex of point 56 has passed the string, and the apex of point 57 is 40 ready to pass the string. The string, however, is in contact with both points 56 and 57, but on opposite sides of the points respectively, and toward the body of the bar from the apexes. Contact of string 55 with point 56 creates a resistance against upward movement of bar 52; and contact of string 55 with point 57 creates a resistance against downward movement of bar 52.

There is thus a stability in this position, operating against displacement of the bar in either direction. The player can feel that a pair of adjacent points is in contact with the string, for he detects the resistance thus created against movement of the bar.

In the form of the invention just described the 55 body 1 of the instrument is shown as of conventional shape. In the form of the invention illustrated in Figs. 9, 10 and 11 and 12, the body 58 is of a different form. It is so shaped that the strings 59, 60, 61 and 62 form a stepped arrangement. The string 59, furthermore, is shown as a double string. The strings are shown as anchored in the anchor plate 63 (Figs. 9 and 11) appropriately attached to the top of the body 58. The strings converge toward a bridge 64 adjacent the left hand end of the instrument and are tensioned by appropriate manipulation of the tuning pegs 65.

As before, a recess 66 extends through the body 58. In this recess are accommodated the keys 67 70 formed on the ends of the crested bars 68, 69, 70 and 71. Some of these bars, such as 68, 69 and 70 (Fig. 12) are provided with a pair of crests, 83, 84, arranged parallel to each other. These crests 83, 84 contact the string 61 at spaced points. 75 That portion of the string between these points

can be set into vibration, if desired, to produce a tone musically related to the tone produced in the main vibrating section of the string.

The bars 68, 69, 70 and 71 are appropriately supported by the aid of a spring hinge structure 72 (Fig. 9), which provides spring fingers 73, 74, 75 and 76 respectively for the bars.

By virtue of the arrangement of the strings oblique to the neck, it is possible to set these strings into vibration by a force applied in the direction of the arrow 77 (Fig. 11).

This direction is such that a natural motion of the fingers is used, rendering the instrument easy to operate. A pick-up device 78 (Fig. 9) is shown beneath the right hand portions of the strings 56, 60, 61 and 62. The intensity of response of the sound reproduction system fed from the pick-up device 78 may be controlled by the arm 79, operating similarly to arm 48, described in connection with the form of the instrument shown in Figs. 1 to 8.

The control of the free vibrating lengths of the strings 56, 60, 61 and 62 is accomplished in a manner similar to that described in the form of the instrument illustrated in Figs. 1 to 8.

The crests, such as 31, 32 (Figs. 4 and 5) or 83, 84 (Fig. 12) are formed of rigid material, and may conveniently be integral with the respective bars. The crests, however, can be made of yielding or soft material, such as leather, felt, rubber or the like, to act as a damper for the string vibrations. Such dampers are especially useful in connection with bows, either in the form of a conventional violin bow or a rotary disk bow. Figs. 13 to 16 inclusive illustrate such crests arranged in a variety of ways.

Fig. 13 shows a bar 85 having a V shaped groove 86 in which is accommodated a strip 87 of soft material. It may be held in place by any appropriate adhesive. This strip forms a relatively wide crest serving very effectively as a damper. The apexes 91 of the groove 86 serve as definite, rigid stops for the string.

Fig. 14 shows a bar 88 with a soft crest member 89 adhered thereto, and having a more pointed apex than the member 87 of Fig. 13.

In Fig. 15 the soft crest member 90 is shown as rectangular in section. As in Fig. 13, an apex 92 of the rigid type, supplements the yielding crest.

In Fig. 16, a double crested bar 93 is illustrated; one of the crests 94 is rigid, and the other crest 95 is of yielding material.

Where a discontinuous crest is used, such as that formed by points 54 in Figs. 6 and 7, it may be desirable to provide damping means acting on the string between the points of the crest, to obviate any tendency of the vibrating string to rattle against the points. Such damping means may be formed by pads, indicated by 97, of any suitable material such as felt, secured to bar 52 between the points 54 and substantially of the same height as the points.

What is claimed is:

1. In a mechanism for adjusting the free length of a tensioned string for a musical instrument, a bar having one or more crests on one side thereof and engaging said string, and means for moving said bar in a direction to pass the string, to cause the crests to move progressively with respect to the string.
2. In a mechanism for adjusting the free length of a tensioned string for a musical instrument, a bar having a crest engaging the string, and means for moving the bar so that the apex of the crest

moves past the string substantially in a plane to cause the crest to move progressively with respect to the string.

3. In a mechanism for adjusting the free length of a tensioned string for a musical instrument, a bar having a crest engaging the string, and means for movably supporting the bar for angular movement such that the apex of the crest moves past the string substantially in a plane to cause the crest to move progressively with respect to the string.

4. In a mechanism for adjusting the free length of a tensioned string for a musical instrument, a bar having a crest engaging the string, and means for movably supporting the bar for angular movement such that the apex of the crest moves substantially in a plane past the string to cause the crest to move progressively with respect to the string, comprising a spring hinge to which the bar is joined, said hinge extending transversely of the string.

5. In a mechanism for adjusting the free length of a tensioned string for a musical instrument, a key for operating said mechanism, and means forming a hinge for the key, and extending transversely of the string, said key having an extension for finger manipulation, and extending generally in the same direction as the string.

6. In a stringed musical instrument, a body, a neck attached to the body, one or more tensioned strings disposed above the neck and body, and means for adjusting the free vibrating length of a string, including a key extending below the neck and terminating in a recess in the neck.

7. In a stringed musical instrument, a body, a neck attached to the body, one or more tensioned strings disposed above the neck and body, and means for adjusting the free vibrating length of a string, including a bar, and means for hingedly mounting said bar on said body, for movement toward and away from the neck and past the corresponding string, said bar having a string contacting crest.

8. In a stringed musical instrument, a body, a neck attached to the body, one or more tensioned strings disposed above the neck and body, and means for adjusting the free vibrating length of a string, including a bar, and means for hingedly mounting said bar on said body, for movement toward and away from the neck and past the corresponding string, said bar having a string contacting crest, as well as a key formed at the free end thereof, and extending into a recess below the neck.

9. In a stringed musical instrument, a body, a plurality of tensioned strings disposed over the body, a bar extending between a pair of adjacent strings and having a crest on each side thereof, respectively engaging said strings, and means for moving the bar to adjust the points of contacts between the crests and the respective strings.

10. In a mechanism for adjusting the free length of a tensioned string for a musical instrument, a bar having a series of elevated points lying substantially in a plane and adapted to engage the string, and means for moving the bar so that the apexes of the points move in said plane to pass the string, the string extending in a direction parallel with said plane and transverse to the direction of said movement.

11. In a mechanism for adjusting the free length of a tensioned string for a musical instrument, a bar having a series of elevated points lying substantially in a plane and adapted to engage the string, and a hinge structure for the

bar, restraining movement of the bar so that said points move in said plane, the string extending in a direction parallel with said plane and transverse to the direction of said movement.

12. In a stringed musical instrument, a body, strings over the body, adjustable means for contacting the strings to determine the free vibrating lengths thereof, and an electrical pick-up device for the vibrations, and operated by transmission of vibrations from the strings through said contacting means.

13. In a mechanism for adjusting the free length of a tensioned string for a musical instrument, a bar having a plurality of crests for engaging the string at points on each crest, said crests extending lengthwise of the bar and lying substantially in a plane, and means for moving said bar to cause said crests to move in said plane to pass the string, the string extending in a direction parallel with said plane and transverse to the direction of said movement.

14. In a stringed musical instrument, a body, a plurality of tensioned strings disposed over the body, a plurality of bars for adjusting the free vibrating length respectively of the strings in response to movement of the bars, and means associated with each bar for restraining movement of said bar to a direction past the respective string, the strings forming a series lying obliquely to the said direction of movement.

15. In a mechanism for adjusting the free length of a tensioned string for a musical instrument, a bar having one or more crests on one side thereof and engaging said string, at least one of said crests being yielding, and means for moving said bar in a direction to cause the crest to move progressively with respect to the string.

16. In a mechanism for adjusting the free length of a tensioned string for a musical instrument, a bar having a groove along a side thereof, said groove having walls with crests at the upper ends, a yielding crest member in the groove, said crest member and the wall crests engaging said string, and means for moving said bar in a direction to cause the crests and crest member to move progressively with respect to the string.

17. In a mechanism for adjusting the free length of a tensioned string for a musical instrument, a bar having a crest engaging the string, the apex of said crest lying substantially in a plane, and means for movably mounting the bar for angular movement such that the apex of the crest moves in said plane, the string extending

in a direction parallel with said plane and transverse to the direction of said movement, said crest being bowed toward the string, the high part of the bow being at an intermediate place along the length of the crest.

18. In a mechanism for adjusting the free length of a tensioned string for a musical instrument, a bar having a crest engaging the string, the apex of said crest lying substantially in a plane, and means for movably mounting the bar for angular movement such that the apex of the crest moves in said plane, the string extending in a direction parallel with said plane and transverse to the direction of said movement, at least

19. a portion of said crest being arched in the direction of motion of the crest, to maintain the angle formed between the crest and the string at a favorable value for all relative positions of that portion of the crest and the string.

20. In a mechanism for adjusting the free length of a tensioned string for a musical instrument, a bar having a series of elevated points lying substantially in a plane and adapted to engage the string, means for moving the bar so that the apexes of the points move substantially in said plane, the string extending in a direction parallel with said plane and transverse to the direction of said movement, and damping means on the bar adapted to contact the string between said points.

21. In a mechanism for adjusting the free length of a tensioned string for a musical instrument, a bar having a crest engaging the string, the apex of said crest lying in a plane, and means for moving the bar so that the apex of the crest moves in said plane, the string extending in a direction parallel with said plane and transverse to the direction of movement of the crest, whereby movement of the bar causes said apex to move progressively with respect to the string.

22. In a mechanism for adjusting the free length of a tensioned string for a musical instrument, a bar having a crest engaging the string, the apex of said crest lying in a plane, and means for movably supporting the bar for angular movement such that the apex of the crest moves in said plane, the string extending in a direction parallel with said plane and transverse to the direction of movement of the crest, whereby movement of the bar causes said apex to move progressively with respect to the string.

JOHN W. McBRIDE.
